THE NORRIS PETERS CO., PHOTO-LITHO., WASHINGTON, D. C.

UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

THREAD-CONTROLLER FOR SEWING-MACHINES.

1,142,360.

Specification of Letters Patent.

Patented June 8, 1915.

Application filed November 18, 1908. Serial No. 463,256.

To all whom it may concern:

Be it known that I, LANSING ONDERDONK, a citizen of the United States, residing at New York, in the county of New York, State 5 of New York, have invented certain new and useful Improvements in Thread-Controllers for Sewing-Machines, of which the following is a description, reference being had to the accompanying drawing and to the letters 10 and figures of reference marked thereon.

The invention relates to new and useful improvements in thread controllers for sewing machines, and has for its object to provide a thread controller which shall be positive in its movements, quick in its action, and which shall control the thread during substantially all the movements of the 15 needle.

A further object of the invention is to 20 provide means whereby the various parts of a controller of the above character, may be quickly adjusted, so as to vary, if desired, the action of the thread controller on the thread.

25 Still further objects of the invention will in part be obvious, and will in part be hereinafter more fully described.

In the drawings, Figure 1 is an end view 30 of a sewing machine with the face plate removed, showing my improved thread controller applied thereto; Fig. 2 is a side view, partly in section, of the head of the machine, showing my improved controller; Fig. 2^a is 35 a diagrammatic view of the thread and thread guides. Fig. 3 is a detail view, showing the connection of the thread controller to the needle bar link; Fig. 4 is a side view, showing the connection of the controller to the needle bar; Fig. 5 is a detail view, showing 40 the connection of the adjustable eyelet to the presser bar; Fig. 6 is an end view, showing the parts of a sewing machine of a different character, having my improved thread controller applied thereto; Fig. 7 is 45 an end view, showing the thread controller and needle bar in a different position; Fig. 8 is a side view of the head of the machine, having my thread controller with parts broken away to show the operating mechanism for the controller; and Fig. 9 is a diagrammatic view, showing the operation of 50 my improved thread controller.

The sewing machine as herein shown, consists of a bed plate 1 having a standard 2 55 carrying an overhanging arm with a needle

head 3, at its forward end. A needle bar 4 reciprocates in bearings 5 and 6. The needle bar, as herein shown, is a short needle bar, which does not extend above the head of the machine, but reciprocates at its upper end in a depending bearing 6, suitably supported by the head of the machine. 60

The needle bar 4 carries a needle 7 at its lower end. Coöoperating with the needle 7 is a looper 8, which, as herein shown, is of the vertical oscillating type. The presser bar 9 is of the ordinary construction, and carries a presser foot 10 at its lower end. The needle bar 4 is reciprocated by means of the link 11, which is pivoted at its lower end to a collar 12, secured to the needle bar 4, and at its upper end to the crank pin 13 of the driving disk mounted on the forward end of the main shaft 14, which is rotated by the usual belt wheel 15. 65

The thread-controlling arm 15 is provided with a laterally projecting thread-engaging portion 16, which swings between guides 17, 18, carried by a bracket 19, which is adjustably attached to the front plate of the machine by means of a suitable screw and slot connection. The thread controlling arm 15 is secured to a short shaft 20, which is mounted in a suitable lug 21 projecting from the casing of the machine. Said shaft 20 is also 70 provided with an arm 22, which extends downward therefrom, and which is connected to a link 23, which link 23 is in turn pivoted to a short arm 24, which extends rearward from the link 11. 75

It will readily be seen that as the needle bar is reciprocated, the link 23 will cause the thread controller 15 to oscillate back and forth between the thread guides 17 and 18. The thread as it passes from the supply to the forward end of the machine, is led through a thread eyelet 25, secured to the head of the machine, and thence through an eyelet 26 carried at the forward end of an arm 27 pivoted on a shaft 28. After passing through 80 the eyelet 26, the thread is led through an eyelet 29, which is secured to the needle bar by suitable screws 30, so as to move up and down with the needle bar. After leaving the eyelet 29 the thread passes through the 85 thread guides 17 and 18 and lies in the path of the laterally projecting thread-engaging portion 16 of the thread-controlling arm 15. From the thread guide 18, the thread is led to the eye of the needle. 90

The arm 27 carrying the thread guide 26 is connected to the presser bar so that the position of the thread eye 26 varies according to the thickness of the fabric. In Fig. 5 5 I have shown one way of connecting said thread arm to the presser bar. In this embodiment of my invention, the shaft 28 is provided with an arm 31, which has a rack 10 engaging a pinion 32 mounted on the head of the machine, which pinion 32 engages a rack 33 secured to the presser bar 9. As the presser bar is raised and lowered by the varying thicknesses of fabric, a similar movement will be imparted to the thread 15 guide 26.

In Figs. 6 to 9 inclusive, I have shown my thread controller applied to a machine wherein the looper oscillates about a horizontal shaft and the needle bar extends 20 above the head of the machine and co-operates with a thread eye mounted on the head of the machine. In this construction, the needle bar 4, carrying the needle 7, co-operates with a looper 8^a. The needle bar is 25 reciprocated by the link 11 from the main shaft. The thread-controlling arm 15 is connected by means of a link 23^a directly to the pivotal connection between the link 11 and the collar 12 on the needle bar. In this 30 type of machine, there is sufficient room to give the necessary length of link so that it is not necessary to provide the needle lever link with an extension in which to pivot the link that operates the thread-controlling 35 arm, as shown in Figs. 1, 2, 5, inclusive. The operation, however, of the thread-controlling arm is practically the same in both types of machines. The needle bar extends above the head of the machine, and is provided with a thread guide 34. Co-operating 40 with the thread guide 34 is a thread arm 35 carrying a thread eye 36. Said thread arm 35 is connected by means of a link 37 to a bracket 38, carried by the presser bar 9. Co- 45 operating with the thread-controlling arm 15 are the thread guides 17 and 18, which are secured to a bracket 19 adjustably attached to the machine, as above described. The arm 15, as herein shown, is pivoted directly 50 to the link 23^a, and is pivoted also to a bearing 39, which is adjustably secured in a slot 40 in the cover plate of the machine, by means of a set screw 41.

In Fig. 9, I have diagrammatically shown 55 the operation of my thread-controlling arm, which is illustrated in Figs. 6 to 8. The operation of the thread-controlling arm in Figs. 1 to 5 is precisely the same and may be followed from the diagrammatic view shown 60 in Fig. 9. When the needle bar is at the upper end of its stroke, the needle thread is substantially taut, as the previous stitch is set by the last part of the movement of the needle bar on its up stroke. As the needle 65 bar moves from the position indicated at 1,

Fig. 9, to the position indicated at 2, the thread-controlling arm moves against the needle thread, and as it moves away from a straight line connecting the thread eye 36 with the eye of the needle, the needle thread 70 is taken up by this movement of the thread-controlling arm. As soon as the needle thread is brought into contact with the thread guides 17 and 18, the thread-controlling arm then takes up the thread much 75 faster. When the needle has reached the position 3, the link connecting the thread controller with the needle bar is substantially at right angles with the needle bar and the thread-controlling arm has reached its extreme 80 forward position. During this part of the movement of the needle and the thread-controlling arm, the thread controller has operated to take up the slack, given by the downward movement of the thread guide 85 34 relative to the thread eye 36 in Fig. 7, or by the movement of the thread guide 29 relative to the thread eye 26 in Fig. 2, and said thread controller also takes up the slack in front of the needle; that is, the 90 thread controller pulls the thread back through the eye of the needle, so as to prevent the thread from getting in the path of the needle point. As the needle continues its downward stroke from the position indicated at 3 to the position indicated at 4, Fig. 9, the thread-controlling arm moves back, giving up the slack to the needle. The needle eye passing beneath the surface of the fabric, doubles the thread, of course, upon 100 itself, and requires slack in order to allow the needle to move to the lower end of its stroke. The thread controller 15, however, merely gives to the needle sufficient thread, so that it may move well down between the 105 looper body and the looper thread running from the eye of the looper to the previous stitch, and as the needle continues its downward movement, the looper sheds the needle loop of the previous stitch. By giving a 110 comparatively small amount of slack to the needle at this time, the needle will operate to draw on the needle thread and hold the needle loop of the previous stitch close around the body of the looper, so that the 115 needle point may pass between the said needle loop on the body of the looper and the looper thread running from the eye of the looper to the previous stitch. Furthermore, as soon as the previous needle loop is 120 shed from the looper, the continued downward movement of the needle draws said shed needle loop well up to the under side of the material. At the same time sufficient slack is given to the needle thread, so that when the needle point is at its lowest position, the thread is comparatively slack in the eye of the needle, thus obviating a strain on the thread at this time, which would cause it to "kink," if not break, and thus 125 130

have a tendency to make a bad loop on the reverse movement of the needle.

As the needle starts on its upward stroke, the link connecting the thread controller with the needle bar will at once move the thread controller into contact with the needle thread, and the needle thread will be drawn up. This movement of the thread controller, causes the thread to draw through the eye of the needle slightly, thus giving a smooth thread for the formation of the loop, which will loop better than a crimped thread. Furthermore, this movement of the thread controller drawing on the thread as the needle starts its upward movement, prevents the formation of too large a loop, which might turn sidewise in the eye of the needle, so that the looper could not engage it, thus causing a skipped stitch, also doubling of thread against the work on the opposite side, when the eye of the needle is moving up into the work, which would cause said eye to cut or break the thread. As the needle continues its upward movement, the thread controller is drawn back, giving up all its slack thread, which will be taken up by the movement of the thread guide 34, above the thread eye 36, and as the thread guide 34 reaches the extreme upper end of its stroke, the thread will be pulled up, so as to set the stitch. At this time, the thread controller is at the rear end of its stroke, so that the draft on the thread is substantially a straight line from the eye at the top of the needle bar to the eye of the needle. This straight pull on the needle thread insures a better tightening of the stitch than if drawn over intermediate thread eyes, which cause an angle in the thread at the time of the setting of the stitch.

It will thus be seen that I have provided a thread controller which moves back and forth twice for each reciprocation of the needle, taking up the slack thread and giving up thread at the proper time, so that the needle and looper will operate with certainty to form the stitch, and so that a tight stitch may be produced.

By adjusting the position of the fulcrum 39, of the thread controller 15, Figs. 6 to 8, I may vary the controlling action on the thread of the thread controller. The fulcrum is so located in Fig. 6 that the connection between the link and the controller is at a point half way between the two extremes of the needle bar's throw, and in this position of the parts, the reciprocations of the thread controller will be the same for the upper and lower half of the movement of the needle bar. If the fulcrum stud of the thread controller is moved up, it carries the point of the connection between the link and the controller above the center of the needle bar stroke, and consequently the outward movement of the controller will be

quicker on the first of the needle bar's descent, and the thread controller will move in to a point near the needle bar. This will cause the thread controller to take up the slack and give it up quicker than when in the central position, and also to give up more slack. It will not, however, take up the slack on the first half of the upward movement of the needle bar as fast. By lowering the fulcrum of the controller, so that the connection between the link and the controller is below the center of the needle bar stroke, the opposite result is secured. In the construction shown in Figs. 1 to 5, inclusive, I accomplish the same adjustment of the thread controller by adjusting the connection between the link 23 and the arm 22, which is secured to the shaft supporting the thread controller. The arm 22 is slotted so as to provide for this adjustment.

Having thus particularly described my invention, what I claim as new and desire to secure by Letters Patent is:—

1. The combination of a needle bar, a needle, means for reciprocating the needle bar, a thread-carrying looper movable into and out of the needle thread loop for locking a loop of looper thread with the needle thread loop, a take-up for setting the stitch and a slack thread-controlling mechanism including, a thread arm, thread guides co-operating with said thread arm, and means for moving said thread arm away from and toward the thread guides during the downward movement of the needle bar, whereby the needle thread is taken up on the first part of the downward movement of the needle, and whereby slack is given up to the needle thread on the last part of the downward movement of the needle.

2. The combination of a needle bar, a needle carried thereby, means for reciprocating the needle bar, a thread-carrying looper, means for moving the thread-carrying looper into and out of the needle loop, so that a loop of looper thread is locked with the needle loop, a take-up for setting the stitch and a slack-thread-controlling mechanism including a thread arm, thread guides co-operating with said thread arm, means for moving said thread arm away from and toward said thread guides on the upward movement of the needle, whereby the needle thread is taken up as the needle begins its upward movement and the needle loop thrown out by the needle for the entrance of the looper reduced, and whereby slack is given up to the needle on the last part of its upward movement, and means for taking up the slack given up by the thread arm and setting the stitch as the needle bar reaches the upper end of its stroke.

3. In combination with a needle bar, a needle carried thereby, means for recipro-

cating said needle bar, a thread-carrying looper, means for moving said thread-carrying looper into and out of the needle loop, so that a loop of looper thread is locked with the needle loop, a thread-guiding eye carried by the upper end of the needle bar, a thread guide coöoperating therewith and so disposed that the thread eye in the needle bar moves above said thread guide to take up the thread and set the stitch, and a slack thread controlling mechanism including a thread arm, thread guides coöperating with said thread arm, and means for moving said thread arm away from and toward the thread guides on the downward movement of the needle bar, and away from and toward said thread guides a second time on the upward movement of the needle bar.

4. The combination of a needle bar, a needle, means for reciprocating the needle bar, a thread-carrying looper movable into

and out of the needle loop for locking a loop of looper thread with the needle loop, a take-up device for setting the stitch, and a slack-thread-controlling mechanism including a thread arm disposed substantially parallel with the needle bar, thread-guides coöperating with said thread arm, a link connecting said thread arm with said needle bar and operating to reciprocate the thread arm twice for one reciprocation of the needle bar, and means whereby the fulcrum of the thread arm may be adjusted in a direction substantially parallel with the movement of the needle bar. 35

In testimony whereof I affix my signature, in presence of two witnesses.

LANSING ONDERDONK.
